UNITED STATES PATENT OFFICE.

CARLETON RUHE, OF NEW YORK, N. Y.

LEATHER SETTING-OUT OR UNHAIRING MACHINE.

Application filed July 30, 1920. Serial No. 400,072.

To all whom it may concern:

Be it known that I, CARLETON RUHE, a citizen of the United States, residing at 1000 Park Avenue, city, county, and State of New York, have invented certain new and useful Improvements in Leather Setting-Out or Unhairing Machines, of which the following is a specification.

My invention relates to a machine for performing certain operations in working upon leather and may be called a setting-out or unhairing machine. The machine is intended to work at high speed and the series of three cylinders with different spiral pitch blades run at different rates of speed and all three cylinders play simultaneously upon the leather as it is being drawn through the machine. The problem of taking wrinkles out of leather also termed "setting-out" is important and difficult. Leather which has been tanned still shows the wrinkles that are natural to the hide of the animal. These wrinkles which occur in the leather are of much the same nature as the wrinkles in the human skin, only somewhat coarser. They are very difficult to remove from all parts of the leather, the removal being usually done by hand. Leather free from wrinkles commands a higher price as when used for sole leather, whereas wrinkled leather goes to the manufacturer of seconds. The wrinkles are distributed over the leather to a varying degree and are of varying depth, the deepest and most difficult wrinkles to remove being embedded in the neck and shoulders.

The unhairing or depilation includes the mechanical removal of the loosened hair on the hide and skins and it is the object of my invention to provide a machine which will accomplish these operations of setting out and unhairing in a simple, effective and satisfactory manner and which will accomplish the setting-out operation on various grades and kinds of leather including both sole leather and upper leather, the stock being made out of cattle hides.

In accordance with my invention I accomplish the widely different results above indicated as to different kinds of leather and as to their varying nature by providing a rotary machine in which three work cylinders are combined with two bed rollers giving four lines of contact or fields of operation for the work cylinders and by progressively

varying the treatment of the leather while in the machine dividing the operations into three steps or stages so that when taking out wrinkles, for example, the difference in peripheral speed of the wrinkle-removing devices of work cylinders may be selected and graduated to carry out the operation most efficiently.

I also so arrange the work cylinders with relation to the bed rolls that a loop is made in the leather while passing thru the machine and while acted upon by the work cylinders. In this way the leather is made to hug the periphery of a work cylinder and the knives of the cylinder can more effectively and completely perform their operations.

The leather is fed thru the machine at a moderate speed by the feeding or pinch rollers, and altho this speed may be varied I have found in practice a speed of 80 feet a minute is desirable. The peripheries of the work cylinders go as high as 1500 feet a minute. A number of blades are placed upon each cylinder. The leather is thus acted upon say 30 times by the first work cylinder before it leaves the field of operation of the cylinder. The pitch of the blades on each work cylinder may be varied when building the cylinder. The three work cylinders are provided with blades of different pitch on the different cylinders. In the embodiment of the invention illustrated upon the drawings I provide about a 72 inch pitch for the first and lowest work cylinder, about 42 inch pitch for the second and about 23 for the third or top cylinder. In this way I secure a wide variation of the pitch and provide for an intermediate pitch so that the action of the machine on the leather is more gradual. Because of the easy, long pitch of the first cylinder this spreads out the leather and the wrinkles quietly and gently. It prepares the leather for the next operation of the intermediate work cylinder.

The next cylinder of shorter pitch acts more vigorously on the wrinkles and the third cylinder of the shortest pitch acts most vigorously. The spirals which work from the middle towards the ends of the cylinder smooth out the wrinkles something like two hands working outwardly from the center of the leather.

The speeds of the cylinders also vary. In the form illustrated upon the drawing the

lowest cylinder with a coarse pitch runs at about 800-1000 revolutions per minute, the medium pitch cylinder at 600-800 and the fine pitch cylinder at 400-600, but of course other speeds may be used. The coarse pitch of the high speed cylinder is preferably about 72 inches, each blade making a complete wrap of the cylinder in 72 inches of its length. The intermediate cylinder carries 10 blades of about 42 inch pitch and the fine pitch cylinder about 23 inch pitch. These dimensions may be varied. Lower pitches may be used. The three work or blade carrying cylinders are driven in the opposite direction to the feed of the leather.

Owing to the relative speeds of the work cylinders, the change in direction in the path of the leather, and the drag on the leather produced by the first or lowest work cylinder, the leather is placed under tension while passing along the loop, thus enabling the middle work cylinder to act most effectively.

There is a maximum limit to the speed of the cylinders. The machine thus has a wide range of speeds and pitches and subjects the leather to the action of cylinders of widely varied activities.

For the unhairing operation a machine is provided with sharper blades and a bed roll with a gripping surface is also substituted. The leather has been previously limed as usual to loosen the hairs and the limed leather is sent thru the machine. The three work cylinders are intended to more effectively remove the hair which is removed from the flanks where the fine hair is found and is usually difficult to remove, as well as from the middle of the hide.

The bed rolls are usually coated with a fairly hard rubber composition so as to provide a yielding back for the leather while being operated upon in the machine. The bed rolls are pressed against the work cylinder by a pressure of as much as two tons and this heavy pressure exerted upon the leather during the three stages in which it is operated upon when in the machine aids in efficiently carrying out the work, despite the varying thickness of the leather.

Referring now to the drawings, Fig. 1 illustrates a vertical section of the machine showing the jaws of the machine open, the front of the machine being at the head of the sheet.

Fig. 2 is a vertical side elevation of the right hand side of the machine, the front of the machine being shown at the bottom of the sheet and the jaws of the machine being closed.

Fig. 3 is a vertical elevation of the left-hand side of the machine with its front at the top of the sheet and the jaws of the machine being closed.

Fig. 4 is a front elevation of the machine.

Fig. 5 is a section of the work cylinders and bed and feed rolls with the leather in position and the jaws of the machine closed.

Fig. 6 shows one of the sectional blade carrying work cylinders.

It will be seen that the invention comprises a machine with three work cylinders 1, 2, 3 and two cooperating bed rolls 4, 5. The work cylinders are preferably mounted in the fixed frame 6 of the machine and the bed rolls cooperate therewith. The bed rolls may be mounted in several ways. As illustrated, they are mounted in the sliding frame 7. The frames are heavily built to withstand the high pressures used and the large horse power used by the machine.

Means are provided for mounting upon the work cylinders spiral knives or blades of different pitch and for readily removing the blades or knives and substituting in their place others of the same or different pitch. Altho the pitch of the blades may be considerably varied, I prefer to provide the lowest work cylinder 1 with blades of about 72 inch pitch, meaning thereby that the blade would theoretically make one turn of the cylinder in 72 inches of the latter's length; the intermediate cylinder 2 with blades of about 42 inch pitch and the top work cylinder 3 with blades of about 23 inch pitch. The blades are cast integral with their supporting frames and the frames are made in sections which are strung upon the shaft of the work cylinder.

As illustrated in Fig. 6 the shaft 8 of the work cylinder 1 has strung upon it a plurality of sections 9 on which the cutting blades 10 are integrally cast. These sections are strung upon the shaft, each section being provided with a keyway and the shaft being provided with a key so as to hold the sections in their proper angular position in order that a continuous cutting or working edge may be obtained from the knives or blades. This is preferably effected by making a keyway along the shaft and providing keyways in the sections, so located as to bring the cutting edges of the sections into matching relation.

Suitable nuts 11 and 12 are screwed upon the shaft clamping the cutting sections longitudinally. The other work cylinders are similarly constructed.

Means are provided for producing four fields of operation or contacting areas for the work cylinders upon the leather. I accordingly arrange and move two bed rolls 4 and 5 in such a manner that they will embrace the intermediate work cylinder and also force the leather into contact with the two end work cylinders, when brought into cooperative relation therewith.

The relation between the work cylinders and the bed rolls is such that a loop is formed in the leather, embracing a part of

the periphery of the middle work cylinder, when the bed rolls are in cooperative relation.

In this way the knives of the middle work cylinder have plenty of time to work upon the leather before it leaves the fields of the operation of the cylinder and four areas of contact are formed under heavy pressure between the two bed rolls and the three cooperating work cylinders, as can be readily seen from an inspection of Fig. 5, where the areas of contact are indicated by the reference characters *m*, *n*, *o*, *p* and the loop by the reference character *L*.

15 Means are provided for driving the work cylinders at three different speeds so as to divide the operation into three steps or stages. These means may be varied. As illustrated upon the drawings, the lower-
20 most work cylinder 1 is mounted upon the drive shaft 13 of the machine, the drive shaft carrying fast and loose pulleys 14, 15 and being mounted in the frame of the machine as illustrated in Fig. 4, for example.
25 The drive shaft 13 is driven at the highest speed, say at 800 to 1000 revolutions per minute and in turn by means of the intermediate gear 16 drives the intermediate work cylinder 2 at a lower speed, say at 600 to 800 revolutions per minute. A gear 17 is secured to the other end of the shaft of the intermediate work cylinder 2, i. e. on the left hand side of the machine as illustrated in Fig. 3 and by gears 18, 19 drives the top work cylinder at the lowest speed, say about 400 to 600 revolutions per minute. Means are provided to drive the feeding mechanism. These means may be varied according to the location of the feeding mechanism and the speed desired. In the form illustrated, the top work cylinder as shown in Fig. 2 carries a gear 20 which meshes with a train of gearing 21, 22, 23, 24, 25, thus driving the upper feed or pinch roll 26 at a much lower speed, say about 50 revolutions per minute. Upper feed roll 26 carries a gear 27 with widely spaced teeth so that it may in turn drive the feed roll 28 carrying the gear 29, the latter meshing with the gear 27 when the jaws of the machine are closed.

The bed rolls 4 and 5 are moved by the frictional drag of the leather as the latter is pulled thru the machine by the feed rolls.
55 The feed rolls pull the leather thru the machine in one direction dragging with them the peripheries of the bed rolls and the work cylinders carrying the tools are positively driven so that the tools move oppositely to the direction of the feed of the leather, while working upon the same.

In the form of the invention illustrated, the machine includes two jaws. These jaws comprise the fixed frame 6 and the sliding frame 7. The latter jaw carries the bed

rolls and slides on ways 30 and 31 of the main frame and is guided by guide rods 310 at the upper end. The bed rolls as well as the lower pinch roll are backed by powerful springs 32, one at each end of the roll, these springs being adjustable so as to predetermine the pressure upon the bed roll and also permit the latter to yield slightly. Adjustment is accomplished by means of screws 33 locked in position by lock nuts 34. In this way a pressure of as much as one ton can be exerted upon each bed or feed roll. The bed and feed rolls are covered with rubber so as to provide a yielding surface.

Means are provided, which may be varied, enabling the operator to bring the bed rolls into cooperation with the work cylinders. In the form of the invention illustrated the operator either opens or closes the jaws of the machine by stepping upon a pedal. The jaws remain closed or opened as the case may be until the operator again steps upon the pedal. In the form of the invention illustrated the main drive shaft 13 by means of gear 35 drives a large gear 36 to which is secured a bevel gear 37 which constantly engages the beveled pinion 38 on the rock shaft 39. The latter shaft carries the worm 40. The worm 40 can engage with the worm gear 41 secured to counter shaft 42, the latter carrying two cranks at opposite sides of the machine, each connected to a connecting rod 43 pivoted at 44 to the movable jaw of the machine. By stepping upon the pedal 45 its other end is raised and the link 46 raises the frame 47 carrying one end of the shaft 39 and moves the shaft, thereby throwing the worm 40 into engagement with the worm gear 41. This will bring about a closing or opening of the jaws of the machine as the case may be.

Means are provided for locking the jaws in their closed or opened position, which means may be varied. In the form illustrated the shaft 42 carries a cam 54 secured thereto having two opposite recesses 48 and 49. The bell crank 50 pivoted at 51 is connected at 520 by pivot and slot connection to the frame 47 carrying one end of the shaft 39. A roller 52 or stud is mounted in the far end of the bell crank 50 and is adapted to engage with the recess 48 or 49 as the case may be. A spring 53 pulls the bell crank 50 toward the right of Fig. 1, and pulls the roller 52 into the recess 48, thus locking the movable jaw 7 in open position. When the operator puts his foot upon the pedal the bell crank 50 is rocked and the roller 52 is moved out of the recess 48 just before the worm 40 engages with worm wheel 41. The movable jaw is thus unlocked and the worm 40 engaging with the worm wheel gives the shaft 42 a half revolution, the roller 52 riding on the cam 54 during the operation. After a half revolution of shaft 42 the jaws

have been closed and the roller 52 drops into the recess 49 by reason of the pull of the spring 53. This rocks the bell crank 50 and throws the worm 40 out of engagement with the worm wheel 41, thus maintaining the jaws closed. The leather having been introduced into the machine with the jaws open is fed out of the machine and operated upon by the knives while the jaws are closed, the feed occurring upward and toward the operator. After the leather is out of the machine the operator once more steps upon the pedal, thereby giving the shaft 42 a half revolution and opening the jaws of the machine. With the jaws closed and the leather out of the machine the peripheries of the bed rolls are slightly separated from the knives on the work cylinders so as not to be injured thereby.

With the above construction in mind the operation will be clear. The jaws being wide open, the operator may insert the hide from the front of the machine over the feed roll 28, which is idle at the moment and not driven. He can lay the leather in the machine quickly and position it accurately. He then steps upon the pedal, taking his foot off after the jaw 7 begins to move. The jaws close upon the leather and the work cylinders which act upon the leather while in a loop and at four areas of contact, rapidly remove the wrinkles without injuring the leather. After the leather is delivered from the machine the operator steps upon the pedal which operation by means of the structure already described causes the jaws to open. After the leather is delivered from the machine it may be turned around and subjected once more to the action of the machine.

What I claim is:

1. A leather setting-out or unhairing machine comprising three work cylinders arranged in one jaw of the machine, a pair of bed rolls arranged in another jaw of the machine and cooperating with the three work cylinders, said pair of bed rolls embracing the middle work cylinder, so as to provide a looped path for the leather about said cylinder when acted upon by the machine and arranged to provide four areas of contact formed by pressing the leather against the work cylinder by the two rolls and means for opening and closing the jaws of the machine.

2. A leather setting-out machine comprising three work cylinders arranged in one jaw of the machine, a pair of bed rolls arranged in another jaw of the machine, said bed rolls being arranged to embrace the intermediate work cylinder so as to form a looped path for the leather about said cylinder when acted upon by the machine, means for driving the work cylinders at

three different speeds and means for feeding the leather thru the machine.

3. A leather setting-out machine comprising three work cylinders arranged in one jaw of the machine, a pair of bed rolls arranged in another jaw of the machine, said bed rolls being arranged to embrace the intermediate work cylinder so as to form a looped path for the leather about said cylinder, one of said bed rolls being also arranged to cooperate with the intermediate and one of the outer work cylinders, the other bed roll being mounted to cooperate with the intermediate and the other of the outer work cylinders, thereby producing four areas of contact between the bed rolls and the work cylinders, means for driving the work cylinders and means for opening and closing the jaws of the machine.

4. A leather setting-out machine comprising three work cylinders arranged in the fixed jaw of the machine, a pair of bed rolls arranged in the movable jaw of the machine, said bed rolls being arranged to embrace the intermediate work cylinder so as to form a looped path for the leather about said cylinder, one of said bed rolls being also arranged to cooperate with the intermediate and one of the outer work cylinders, the other bed roll being mounted to cooperate with the intermediate and the other of the outer work cylinders, thereby producing four areas of contact between the bed rolls and the work cylinders, means for driving the work cylinders, means for moving the bed roll jaw toward and from the fixed jaw of the machine, and means for feeding the leather thru the machine.

5. A leather setting-out machine comprising three work cylinders arranged in the fixed jaw of the machine, one above the other, a pair of bed rolls, one above the other, arranged in the movable jaw of the machine, said bed rolls being arranged with their axes in planes intermediate those of the axes of the work cylinder, the bed rolls being arranged to embrace the intermediate work cylinder so as to form a looped path for the leather about said cylinder, one of said bed rolls being also arranged to cooperate with the intermediate and one of the outer work cylinders, the other bed roll being mounted to cooperate with the intermediate and the other of the outer work cylinders, thereby producing four areas of contact between the bed rolls and the work cylinders, means for driving the work cylinders, means for moving the bed roll jaw toward and from the fixed jaw of the machine, and a pair of feed rolls, one in the fixed jaw and the other in the movable jaw for feeding the leather thru the machine.

6. A leather setting-out machine comprising three work cylinders arranged in the

fixed jaw of the machine, a pair of bed rolls arranged in the movable jaw of the machine with their axes above and below the middle work cylinder and coacting therewith so as to form a looped path for the leather about said cylinder, said bed rolls also cooperating with the two end work cylinders thereby producing four areas of contact between the bed rolls and the work cylinders, a pair of feed rolls for the leather, one in the fixed jaw and one in the movable jaw, means for driving the work cylinders at three different speeds and for driving the feed roll in the fixed jaw at a lower speed than the lowest speed of the work cylinders, the bed rolls being freely supported so as to be driven by the leather in its passage thru the machine, and the feed roll in the movable jaw carrying a gear which is driven by the gear on the feed roll of the fixed jaw, when the jaws are closed, a rotatable shaft, connections between said shaft and the movable jaw, means for giving said shaft a half revolution and means for locking said shaft at the end of the half revolution, so as to move and lock the jaw in position.

7. A leather setting out machine comprising three work cylinders arranged in the fixed jaw of the machine, a pair of bed rolls arranged in the movable jaw of the machine with their axes above and below the middle work cylinder and coacting therewith so as to form a looped path for the leather about said cylinder, said bed rolls also cooperating with the two end work cylinders thereby producing four areas of contact between the bed rolls and the work cylinders, a pair of feed rolls for the leather, one in the fixed jaw and one in the movable jaw, means for driving the work cylinders at three different speeds and for driving the feed roll in the fixed jaw at a lower speed than the lowest speed of the work cylinders, the bed rolls being freely supported so as to be driven by the leather in its passage thru the machine, and the feed roll in the movable jaw carrying a gear which is driven by the gear on the feed roll of the fixed jaw, when the jaws are closed, a rotatable shaft, connections between said shaft and the movable jaw and means for rotating said shaft so as to open and close said jaw.

8. A leather setting out machine comprising three work cylinders arranged in the fixed jaw of the machine, a pair of bed rolls arranged in the movable jaw of the machine with their axes above and below the middle work cylinder and coacting therewith so as to form a looped path for the leather engaging the middle work cylinder, said bed rolls also cooperating with the two end work cylinders thereby producing four areas of contact between the bed rolls and the work cylinders, a pair of feed rolls for the leather, one in the fixed jaw and one in the movable jaw, means for driving the work cylinders at three different speeds and for driving the feed roll in the fixed jaw at a lower speed

than the lowest speed of the work cylinders, the bed rolls being freely supported so as to be driven by the leather in its passage thru the machine, and the feed roll in the movable jaw carrying a gear which is driven by the gear on the feed roll of the fixed jaw, when the jaws are closed, a rotatable shaft, connections between said shaft and the movable jaw, means for giving said shaft a half revolution and means for locking said shaft at the end of the half revolution, so as to move and lock the jaw in position.

9. A leather setting out machine comprising three work cylinders arranged in the fixed jaw of the machine a sliding movable jaw, a pair of bed rolls arranged in the movable jaw and cooperating with said three work cylinders so as to produce a looped path about the middle work cylinder and four areas of contact for the leather, a shaft, connections between the shaft and the movable jaw, driving mechanism for rotating said work cylinders and for giving said shaft intermittent half revolutions so as to open and close said jaw.

10. A leather setting out machine comprising three work cylinders arranged in the fixed jaw of the machine, a feed roll arranged above the work cylinders a sliding movable jaw, a pair of bed rolls arranged in the movable jaw of the machine, said bed rolls embracing the middle work cylinder, a feed roll arranged above the bed rolls, a shaft and connections between the shaft and the movable jaw, means for driving said work cylinders and said shaft so as to give said shaft intermittent half revolutions, thereby opening and closing the jaws, said bed rolls and last named feed roll being driven from said work cylinders when the jaws are closed.

11. A leather setting out machine comprising three work cylinders arranged in the fixed jaw of the machine, a feed roll arranged above the work cylinders a sliding movable jaw, a pair of bed rolls arranged in the movable jaw of the machine, said bed rolls embracing the middle work cylinder, a feed roll arranged above the bed rolls, a shaft and connections between the shaft and the movable jaw, means for driving said work cylinders, means for giving said shaft a series of intermittent half revolutions, thereby opening and closing the jaws, means for locking said shaft after each half revolution, thus keeping the jaws open or closed, said bed rolls and last named feed roll being driven from said work cylinders when the jaws are closed.

12. A leather setting out machine comprising three work cylinders arranged in the fixed jaw of the machine, a feed roll arranged above the work cylinders, a sliding movable jaw, a pair of bed rolls arranged in

6
the movable jaw of the machine, said bed rolls embracing the middle work cylinder, a feed roll arranged above the bed rolls, a shaft and connections between the shaft and the movable jaw, means for driving said work cylinders, connections between the driving mechanism and said shaft for giving said shaft a series of half revolutions, thereby opening and closing the jaws, a pedal for throwing said connections in operation, means for locking said shaft after each half revolution, thus keeping the jaws open or closed, said bed rolls and last named feed roll being driven from said work cylinders 15 when the jaws are closed.

13. A leather setting out machine comprising three work cylinders arranged in the fixed jaw of the machine, a feed roll arranged above the work cylinders, a pair of bed rolls arranged in the movable jaw of the machine, said bed rolls embracing the middle work cylinder, a feed roll arranged above the bed rolls, a countershaft and connections between the shaft and the movable 20 jaw, means for driving said work cylinders, a gear carried by said countershaft, a worm adapted to mesh with said gear and to be driven by the drive shaft, and a pedal for throwing said worm into mesh with said 25 gear.

14. A leather setting out machine comprising three work cylinders arranged in the fixed jaw of the machine, a feed roll arranged above the work cylinders, a pair of bed rolls arranged in the movable jaw of the machine, said bed rolls embracing the middle work cylinder, a feed roll arranged above the bed rolls, a countershaft and connections between the shaft and the movable 30 jaw, means for driving said work cylinders, a gear carried by the said countershaft, a worm adapted to mesh with said gear and to be driven by the drive shaft, and means for throwing said worm into and out of engagement with said gear.

15. A leather setting out machine comprising three work cylinders arranged in the fixed jaw of the machine, a feed roll arranged above the work cylinders, a pair of bed rolls arranged in the movable jaw of the machine, said bed rolls embracing the middle work cylinder, a feed roll arranged above the bed rolls, a countershaft and connections between the shaft and the movable 40 jaw, means for driving said work cylinders, a gear carried by said countershaft, a rock shaft, gearing for driving said rock shaft, a worm on said rock shaft adapted to mesh with said gear and means for throwing said worm into and out of engagement with said gear.

16. A leather setting out machine comprising three work cylinders arranged in the fixed jaw of the machine, a feed roll arranged above the work cylinders, a pair of bed rolls arranged in the movable jaw of the machine, said bed rolls embracing the middle work cylinder, a feed roll arranged above the bed rolls, a countershaft and connections between the shaft and the movable 50 jaw, means for driving said work cylinders, a gear carried by said countershaft, a rock shaft, gearing for driving said rock shaft, a worm on said rock shaft adapted to mesh with said gear and means for throwing said worm into and out of engagement with said gear.

17. A leather setting out machine comprising three work cylinders arranged in the fixed jaw of the machine, a feed roll arranged above the work cylinders, a pair of bed rolls arranged in the movable jaw of the machine, said bed rolls embracing the middle work cylinder, a feed roll arranged above the bed rolls, a countershaft and connections between the shaft and the movable 55 jaw, a drive shaft for driving said work cylinders, a gear carried by said countershaft, a rock shaft, gearing between the drive shaft and the rock shaft for driving the rock shaft, reducing gearing carried by the rock shaft adapted to engage with the gear on the countershaft, locking mechanism for the countershaft for locking it at each half revolution, connections between the locking mechanism and the rock shaft 60 and a pedal for moving said rock shaft so as to engage the gearing on the rock shaft with the gear on the countershaft.

18. A leather setting out machine comprising three work cylinders arranged in the fixed jaw of the machine, a feed roll arranged above the work cylinders, a pair of bed rolls arranged in the movable jaw of the machine, said bed rolls embracing the middle work cylinder, a feed roll arranged above the bed rolls, a countershaft and connections between the shaft and the movable 65 jaw, a drive shaft for driving said work cylinders, a gear carried by said countershaft, a rock shaft, gearing between the drive shaft and the rock shaft for driving the rock shaft, reducing gearing carried by the rock shaft adapted to engage with the gear on the countershaft, locking mechanism for the countershaft for locking it at each half revolution, connections between the locking mechanism and the rock shaft 70 and a pedal for moving said rock shaft so as to engage the gearing on the rock shaft with the gear on the countershaft.

19. A leather setting out machine comprising three work cylinders arranged in the fixed jaw of the machine, a feed roll arranged above the work cylinders, a pair of bed rolls arranged in the movable jaw of the machine, said bed rolls embracing the middle work cylinder, a feed roll arranged above the bed rolls, a countershaft and connections between the shaft and the movable jaw, a drive shaft for driving said work cylinders, a gear carried by said countershaft, a rock shaft carrying a bevel gear 75 at one end in mesh with a bevel gear driven by the drive shaft, a worm carried by the other end of the rock shaft, a frame supporting the distal end of the rock shaft, a cam provided with two recesses and two faces carried by the countershaft, a bell crank carrying a roller at one end adapted to engage said recesses and being pivoted at the other end to said frame, and links and a pedal connected to said frame.

20. A combined leather setting out and unhauling machine comprising three work cylinders with removable and replaceable sections each carrying spiral blades, the blades on the cylinders being of different pitch and of different sharpness in accordance with the work done by the machine, the said three work cylinders being located in one jaw of the machine, a sliding carriage forming the other jaw of the machine, a pair of bed rolls located in said carriage, springs for backing said bed rolls, said bed rolls embracing the middle work cylinder, a feed roll carried by one of said jaws, a countershaft and connecting rods for reciprocating said sliding carriage and a driving shaft and connections for operating said countershaft and driving said work cylinders and feed roll.

21. A combined leather setting out and unhauling machine comprising three work cylinders with removable and replaceable sections each carrying spiral blades, the blades on the cylinders being of different pitch and of different sharpness in accord-

ance with the work done by the machine, the said three work cylinders being located in one jaw of the machine, a pair of upright frames forming part of a sliding carriage 5 constituting the other jaw of the machine, a pair of bed rolls located in said carriage, springs for backing said bed rolls, said bed rolls embracing the middle work cylinder, a feed roll carried by one of said 10 jaws, a pair of ways guiding and supporting the upright frames, guide rods for guiding the upper end of said frames, and means for reciprocating said carriage.

20. A combined leather setting out and 15 unhairing machine comprising three work cylinders with removable and replaceable sections each carrying spiral blades, the blades on the cylinders being of different pitch and of different sharpness in accordance with the work done by the machine, the said three work cylinders being located in one jaw of the machine, a pair of upright frames forming part of a sliding carriage constituting the other jaw of the machine, 20 a pair of bed rolls located in said carriage, springs for backing said bed rolls, said bed rolls embracing the middle work cylinder, a feed roll carried by one of said jaws, a pair of ways guiding and supporting the 25 upright frames, guide rods for guiding the upper end of said frames, means for reciprocating said carriage, and means for locking said carriage in its open and closed position.

35. 21. A leather setting out or unhairing machine comprising three blade carrying work cylinders arranged to work on one side of the leather, a pair of bed rolls contacting with the opposite side of the leather, and 40 cooperating with the work cylinders so as to provide a looped path for the leather, the loop engaging the middle work cylinder when acted upon by the machine and arranged to provide four areas of contact 45 formed by pressing the leather against the work cylinders by the two rolls and means for bringing the bed rolls and work cylinders into and out of cooperative relation with each other.

50. 22. A leather setting out or unhairing machine comprising three blade carrying work cylinders arranged to work on one side of the leather, a pair of bed rolls contacting with the opposite side of the leather and 55 cooperating with the work cylinders so as to provide a looped path for the leather when acted upon by the machine and arranged to provide four areas of contact formed by pressing the leather against the 60 work cylinders by the two rolls, the loop engaging the middle work cylinder, mechanism for bringing the bed rolls into and out of cooperative relation with the work cylinders, and a pedal for controlling said 65 mechanism.

23. A leather setting out or unhairing machine comprising three work cylinders, a pair of bed rolls cooperating with the work cylinders, so as to provide a looped path for the leather when acted upon by the machine and arranged to provide four areas of contact formed by pressing the leather against the work cylinders by the two rolls, the intermediate work cylinder engaging 70 said loop, means for bringing the bed rolls and the work cylinders into and out of cooperative relation with each other, and means for locking the rolls and cylinders in and out of cooperative relation.

24. A leather setting out or unhairing machine comprising three work cylinders, a pair of bed rolls cooperating with the work cylinders so as to provide a looped path for the leather when acted upon by the machine and arranged to provide four areas of contact formed by pressing the leather against the work cylinders by the two rolls, the intermediate work cylinder engaging said loop, mechanism for bringing the bed rolls into and out of cooperative relation with 85 the work cylinders, locking means for locking the bed rolls in and out of working position and a pedal for controlling said mechanism and said locking means.

25. A leather setting out machine comprising three work cylinders, a pair of bed rolls, said bed rolls being arranged to embrace the intermediate work cylinder so as to form a looped path for the leather about 90 said cylinder when acted upon by the machine, means for driving the work cylinders at three different speeds and means for feeding the leather thru the machine.

26. A leather setting out machine comprising three work cylinders, a pair of bed rolls, said bed rolls being arranged to embrace the intermediate work cylinder so as to form a looped path for the leather about 95 said cylinder, one of said bed rolls being also arranged to cooperate with the intermediate and one of the outer work cylinders, thereby producing four areas of contact between the bed rolls and the work cylinders, means for driving the work cylinders, and means for bringing the bed rolls and work cylinders into and out of cooperative relation with each other.

27. A leather setting out machine comprising three work cylinders, a pair of bed rolls, said bed rolls being arranged to embrace the intermediate work cylinder so as to form a looped path for the leather about 100 said cylinder, one of said bed rolls being also arranged to cooperate with the intermediate and one of the outer work cylinders, the other bed roll being mounted to cooperate with the intermediate and the other of the outer work cylinders, thereby producing 105 four areas of contact between the bed rolls and the work cylinders, means for driving 110

the work cylinders, mechanism for bringing the bed rolls and work cylinders into and out of cooperative relation with each other, means for locking the rolls and cylinders in and out of cooperative relation, a pedal for controlling said mechanism and locking means and means for feeding the leather to the machine.

28. A leather setting out machine comprising three work cylinders, a pair of bed rolls, said bed rolls being arranged to embrace the intermediate work cylinder so as to form a looped path for the leather about said cylinder when acted upon by the machine, means for driving the three work cylinders so that the speed ratio between the high speed cylinder and the low speed cylinder is about two to one, and the speed ratio between the intermediate cylinder and the low speed cylinder is about three to two, and means for feeding the leather thru the machine.

29. A leather setting out machine comprising three work cylinders, carrying blades at three different pitches, namely one pitch for each work cylinder, a pair of bed rolls, said bed rolls being arranged to embrace the intermediate work cylinder so as to form a looped path for the leather about said cylinder when acted upon by the machine, means for driving the three work cylinders so that the speed ratio between the high speed cylinder which carries the coarse pitch blades and the low speed cylinder which carries the blades of fine pitch, is about two to one, and the speed ratio between the intermediate

cylinder which carries blades of intermediate pitch and the low speed cylinder is about three to two, and means for feeding the leather thru the machine in a direction opposite to that of the blades on the cylinders when contacting with the leather.

30. A leather setting out machine comprising three work cylinders, carrying blades at three different pitches, namely one pitch for each work cylinder, a pair of bed rolls, said bed rolls being arranged to embrace the intermediate work cylinder so as to form a looped path for the leather about said cylinder when acted upon by the machine, means for driving the three work cylinders so that the speed ratio between the high speed cylinder which carries the blades of about 72 inch pitch and the low speed cylinder which carries the blades of about 23 inch pitch, is about two to one, and the speed ratio between the intermediate cylinder which carries blades of about 42 inch pitch and the low speed cylinder is about three to two, and means for feeding the leather thru the machine in a direction opposite to that of the blades on the cylinders when contacting with the leather and at a speed which is less than that of the blades.

In testimony whereof, I have signed my name to this specification, in the presence of two subscribing witnesses.

CARLETON RUHE.
